UNITED STATES PATENT OFFICE

2,397,946

TORPEDO DEPTH CONTROL SYSTEM

Samuel T. Bussey, United States Navy

Application March 23, 1945, Serial No. 584,474

10 Claims. (Cl. 114—25)

(Granted under the act of March 3, 1883, as
amended April 30, 1928; 370 O. G. 757)

This invention relates to torpedoes, and more specifically, to improved means for controlling the travel of the torpedo while it is submerged.

As constructed, at the present time, torpedoes are provided with horizontal tail planes which are actuated once the torpedo is submerged to bring it to a given depth, and to maintain it at a substantially constant depth throughout the course of its travel. This is accomplished by a depth engine which is operably connected to the horizontal planes to tilt the horizontal planes in one direction or the other in response to a diaphragm exposed to water pressure. By presetting the diaphragm so that it will respond to a given pressure, the depth engine may be caused to bring the torpedo to the given depth. In combination with the hydraulic diaphragm, there is operably connected, a pendulum which is suspended to swing about a horizontal axis and in a vertical plane longitudinally of the torpedo, and its connection to the depth engine keeps the torpedo in a horizontal plane once it has attained its predetermined depth. In a torpedo so controlled, the momentum of the torpedo and its inertia as it enters the water and seeks to gain its position, causes it to overrun the given depth in one direction or the other. Hence, the path of the torpedo will be substantially sinusoidal in character for a considerable distance before it reaches a stabilized depth.

It is an object of this invention to provide means for dampening the sinusoidal path of the torpedo, that is, to reduce the hunting of the torpedo for its predetermined level of run, the means being of such a nature that it may readily be installed in existing torpedoes without undue redesigning and which will be effective and accomplish the desired results.

As illustrated herein, the invention resides in horizontal planes arranged at both the nose and the tail of an underwater body which is self-propelled, specifically, a torpedo, the planes at the nose being adapted to govern the depth of the torpedo and the planes at the tail being adapted to govern the angle at which the torpedo moves, the planes at the nose and tail being operable independently of each other. The nose planes are comparatively larger in area than the tail planes and extend laterally from the torpedo outwardly, the lateral edges terminating approximately in a projection of the largest diameter of the torpedo. The nose planes are actuated by a depth engine, the direction of movement of which is controlled by a hydraulic diaphragm. The hydraulic diaphragm is susceptible of adjustment to cause the depth engine to bring the torpedo to a given depth and to transmit the depth setting from the rear end of the torpedo to the hydraulic diaphragm at the nose which is operably connected to the depth en-

gine, there is a hydraulic cylinder including a piston movable by means of a depth setting screw accessible from the outside of the torpedo near its rear end, a hydraulic conduit connecting the hydraulic cylinder to a second hydraulic cylinder including a second hydraulic piston connected to the diaphragm by way of a spring, the second piston being arranged by movement, to tension the spring and hence to displace the diaphragm from a neutral position so that the depth engine will operate to cause the torpedo to sink to a position in which the pressure on the diaphragm moves it back to its neutral position.

The invention will now be described with reference to the accompanying drawings, in which:

Fig. 1 is a perspective view of an aircraft type of torpedo illustrating depth planes at the nose of the torpedo in accordance with my invention;

Fig. 2 illustrates an aircraft type torpedo partly broken away to show the disposition of the elements which effect operation of the depth planes at the nose and tail;

Fig. 3 is a fragmentary portion of the torpedo at the nose in plan showing the shape of the nose planes;

Fig. 4 is a view partly in section of the hydraulically operated diaphragm for controlling the depth engine; and

Fig. 5 is a section through the depth setting means at the rear end of the torpedo.

Referring to Fig. 1, there is shown an aircraft type of torpedo 10 in perspective, the torpedo being provided at its nose 12 with horizontal nose planes 14 and at its tail 16 with horizontal tail planes 18. The torpedo is also provided with the usual stabilizers 20 and propelling means 22, and while shown herein as an aircraft type torpedo may be any of the well known types of torpedoes. The nose planes 14, as will be seen by reference to Fig. 3, extend laterally outward from near the nose 12 of the torpedo, the forward edges being substantially at right angles to the longitudinal axis of the torpedo, and the rear edges conforming closely to the contour of the nose of the torpedo so that the nose planes are substantially triangular in shape. The lateral edges of the nose planes terminate just short of the projection of the largest diameter of the torpedo, and hence, eliminate any chance of damaging the planes if the torpedo is mounted in a tube or bracket which closely engage the body of the torpedo.

The rear planes 18 are constructed and actuated, as is customary, by the combined operation of a hydraulic diaphragm and a pendulum, this unit being indicated generally by the reference character 24. Briefly, the unit consists of a housing within which there is mounted a diaphragm, the position of which controls a depth steering engine 26. The depth steering engine

is connected to the diaphragm by way of a rod 28 and to the planes 14 by way of a rod 30. The diaphragm is so arranged that it is exposed at one side to air pressure and at the opposite side to water pressure, the water pressure being that which exists because of the depth of the water at which the torpedo is located. On the side of the diaphragm which is exposed to the water, there is connected a spring which may be adjusted to impart an initial tension thereto and hence to displace the diaphragm a given amount with respect to its neutral position. By setting the tension in the spring so that it will require a definite pressure to force the diaphragm from its displaced position to the neutral position, there is provided a convenient method for governing the depth at which the torpedo will run. For example, if the spring is set so that it will take a given number of pounds pressure per square inch to cause it to move from its predetermined position to a neutral position, the torpedo will, when submerged, dive below the surface of the water until a depth is reached where this pressure will exist, whereupon the diaphragm will move to a neutral position and the depth planes will be caused by means of the depth engine, to take a neutral position, whereupon the torpedo will theoretically remain at that position for the length of its run. While the torpedo is running at its given depth, there is, however, a tendency for it to plane upwardly or downwardly with respect to its horizontal axis, and hence, there is provided a free pendulum which will actuate the depth engine to tilt the rudder up or down whenever the torpedo tends to run out of its horizontal plane.

The aforesaid construction is all standard and is employed in standard torpedo constructions, but has a disadvantage in that the torpedo tends to move sinusoidally, particularly in its initial attempt to reach its given depth. This wandering or hunting of the torpedo is undesirable, and it is the purpose of this invention to reduce this effect insofar as possible. Accordingly, there is provided, as illustrated herein, means in the nature of additional planes at the nose of the torpedo. As shown, Fig. 2, the planes 14 at the nose of the torpedo are connected for tilting movement about a horizontal axis passing through the nose of the torpedo to a horizontal shaft 34 suitably mounted in the nose of the torpedo, the shaft having connected thereto a lever 36 and a link 38, the latter being a part of a piston rod which is reciprocated by a depth engine 40. The depth engine 40 receives its power from a compressed air conduit 41 which may be connected to the air flask of the torpedo. The depth setting engine 40 is controlled by a hydraulic unit 42 including a diaphragm somewhat similar to that described generally above, the diaphragm being connected by links 44, 46 and 48 to the depth control engine to regulate the operation of the same. The details of the depth control unit 42 and diaphragm are shown in Fig. 4, and as illustrated therein, consist of a housing 43 having three chambers therein, 46, 48 and 50. The chamber 46 is divided from the chamber 48 by a wall 52 and the chamber 50 is divided from the chamber 48 by a diaphragm 54. Within the chamber 46, there is mounted a piston 56 having a piston rod 58 attached thereto, the latter extending through an aperture 60 formed in the wall 52 and having threaded on its inner end a cup shaped member 62, a nut 64 being threaded on the piston rod to hold the cup in place. On

the upper face of the piston 56, there is formed an annular shoulder 66 over which there is disposed a coil spring 68, the spring abutting the top of the piston and the top of the chamber 46. A spindle 70 is fastened to the diaphragm 54 and has threaded thereon a cupped shaped member 72, which is secured in place by a nut 74. Between cups 62 and 74 there is disposed a spring 76. An aperture 78 is formed in the spindle 70 and through this aperture passes an inner extension of the link 44. The chamber 46 has leading into it, a conduit 80, a gland 82 being provided for this purpose. The conduit 80 extends rearwardly from the nose of the torpedo to a cylinder 84, having a piston 86 therein, the piston 86 being provided with a piston rod 88. The piston rod 88 has a rack 90 cut on its surface which is adapted to mesh with a gear 92 having integral therewith a spur gear 94, the spur gear being adapted to engage a second spur gear 96. The spur gear 96 is fastened to a spindle 98, the free end of which is accessible from the underside of the torpedo, and is provided with a socket 100. The socket 100 is so shaped as to receive an end wrench or any square member and by rotation to move the piston 86 in the cylinder 84. When this is done, a certain amount of hydraulic fluid in the cylinder 84 is forced through the conduit 80 into the chamber 46, and hence, changes the position of the piston 56 which is normally urged downwardly by the spring 68. By changing the position of the piston 56, the tension on the spring 56 may be changed, and hence, the position of the diaphragm 54 may be changed, that is, displaced above or below its horizontal position, as shown in Fig. 4. This in turn changes the position of the link 44, and depending upon the direction in which it is changed will cause the depth engine to be actuated in one direction or the other to tilt the planes 14 up or down. A conduit 102 is led into the chamber 48, this conduit being carried toward the rear of the torpedo and being open to the outside water pressure through an aperture formed in the wall of the torpedo at about its middle section. With this construction, it is evident that if the spring 76 is set so that the diaphragm 54 is drawn upwardly a given amount, it will take a corresponding amount of water pressure on the diaphragm 54 to move the diaphragm back to its original position. Therefore, when the torpedo is dropped in the water, it will begin to sink in the water and will continue to sink until the water pressure on the outside of the torpedo, which is conducted through the conduit 102 to the upper surface of the diaphragm 54 becomes equal to the tension in the spring 76, whereupon it will level out, by reason of the fact that the depth engine 40 will cease to operate. This would be true if there is no overrun of the torpedo. Since there is, however, an overrun due to the momentum of the torpedo, the torpedo will sink beyond the desired depth and the water pressure will force the diaphragm 54 below its neutral position whereupon the depth engine will be started up in its opposite direction, the planes 14 will be tilted in the opposite direction, and the torpedo will begin to rise. This action continues until the proper depth is arrived at and will greatly reduce the hunting inherent in this type of control where only tail planes are employed.

As illustrated herein, and particularly in Figs. 1 and 3, it is desirable to provide means for protecting the nose planes 14, and hence, there are

fastened to the nose of the torpedo, guards 104 which extend in opposite directions from the nose in parallel relation to the forward edges of the planes 14. Preferably, the ends of the guards 104 terminate just beyond the lateral edges of the planes 14, and hence, prevent any damage to these edges.

In preparing the torpedo for a run, the depth setting spindles for both the tail and nose planes are set for the same depth and then the torpedo is launched. As the torpedo enters the water, its initial plunge carries it below the surface and its propellers drive it on down at an angle to the surface. As the pressure becomes greater, the diaphragms move to a neutral position, whereupon the depth engines bring the nose and tail planes to a substantially horizontal position. The impulse of the plunge, however, carries the torpedo beyond the predetermined depth, and hence, the pressure pushes the diaphragms in the opposite direction. This causes the depth engines to again operate to move the planes to a position to cause the torpedo to move back toward its predetermined depth. Due to the fact that both nose and tail planes are employed, the torpedo will attain its predetermined depth much more quickly than if only tail planes were employed.

The invention described herein may be manufactured and used by or for the Government of the United States of America for governmental purposes without the payment of any royalties thereon or therefor.

What is claimed is:

1. An underwater body capable of self-propulsion, said body having horizontal planes at its opposite ends, said planes being independently operable, one of said planes being actuated in response to the water pressure to govern the depth at which the body will travel, and the other being actuated in response to the position of a free pendulum with respect to the longitudinal axis of the body to govern its angle of travel.

2. A torpedo having horizontal planes at the nose and tail, said planes being operable independently of each other, the nose planes being actuated in response to the water pressure to govern the depth at which it will travel and the tail planes being actuated in response to the position of a free pendulum with respect to the longitudinal axis of the torpedo to govern the angle at which it will travel.

3. A torpedo having horizontal planes at the nose and tail, said planes being operable independently of each other, a depth engine operably connected to the planes at the nose, an angle control engine operably connected to the tail planes, means responsive to the differential between the pressure at the desired depth, and the existant pressure to cause said depth engines to tilt the planes in a direction to cause the torpedo to move toward the desired depth, and means comprising a pendulum operable by its position relative to the axis of the torpedo to actuate the angle control engine.

4. A torpedo having horizontal planes near the nose and tail, said planes being operable independently of each other, a depth engine operably connected to the planes at the nose, means operable by the differential in the pressure at the desired depth and the existant pressure to cause the depth engine to tilt the planes in a direction to cause the torpedo to move toward the desired

depth, and means for adjusting the last named means.

5. A torpedo having horizontal planes near the nose and the tail, said planes being operable independently of each other, a depth engine operably connected to the planes at the nose, hydraulically actuated means responsive to the water pressure to effect operation of the depth engine to tilt the planes in one direction or the other, and means for presetting said hydraulically actuated means so that it brings the planes to a horizontal position at a given depth.

10 6. A torpedo having horizontal planes near the nose and the tail, said planes being operable independently of each other, a depth engine operably connected to the planes at the nose, hydraulically actuated means responsive to the water pressure to effect operation of the depth engine to tilt the planes in one direction or the other, means adjustable to preset said hydraulically actuated means so that it brings the planes to a horizontal position at a given depth, and means to effect adjustment of said last named means from outside of the torpedo.

15 7. A torpedo having horizontal planes at the nose and the tail, said planes being operable independently of each other, a depth engine operably connected to the planes at the nose, a diaphragm operably connected to the depth engine

20 30 to effect operation thereof when displaced from a given position, an air pressure chamber at one side of the diaphragm, a spring at the opposite side of the diaphragm, said spring being connected to the diaphragm, means for varying the tension in the spring to displace the diaphragm a given amount from said given position, and a conduit arranged to admit fluid pressure to that side of the diaphragm opposite to the air chamber to cause said diaphragm to move toward said given position.

25 40 8. A torpedo having horizontal planes at the nose and the tail, said planes being operable independently of each other, a depth engine operably connected to the planes at the nose, a diaphragm operably connected to the depth engine, which when shifted from an equilibrium position in one direction or the other effects operation of the depth engine, an air chamber on one side of said diaphragm, a spring on the other side, means 45 50 for setting in a given tension on the spring to displace the diaphragm a predetermined amount from its equilibrium position, said means comprising a hydraulically operated piston, and means operable from the tail end of the torpedo to displace said hydraulic piston a given amount.

55 9. A torpedo having planes at the nose and tail, said planes at the nose having an area which is relatively large as compared to the area of the planes at the tail and being operable independently of the tail planes, and a guard adjacent to the nose planes extending transversely of the nose of the torpedo, and terminating just beyond the lateral edges of the nose planes.

10. A torpedo having horizontal planes at the 60 65 nose and the tail, said planes at the nose extending laterally from opposite sides of the nose and being of comparatively large area, the lateral edges of said planes terminating within a projection of the larger diameter of the torpedo, and guards extending transversely of the torpedo along the forward edges of the planes, said guard terminating just beyond the lateral edges of said planes.

SAMUEL T. BUSSEY.
